UNITED STATES PATENT OFFICE.

RAFAEL V. MEINONG, OF INNSBRUCK, AUSTRIA-HUNGARY, ASSIGNOR OF TWO-THIRDS TO THE FIRM OF OESTERREICHISCHE ASPHALT ACTIENGESELLSCHAFT AND OTTO FREIHERR VON CZEDIK, OF VIENNA, AUSTRIA-HUNGARY.

PERMANENT WAY.

SPECIFICATION forming part of Letters Patent No. 752,403, dated February 16, 1904.

Application filed April 7, 1903. Serial No. 151,536. (No model.)

To all whom it may concern:

Be it known that I, RAFAEL RITTER VON MEINONG, a subject of the Emperor of Austria-Hungary, residing at Innsbruck, Tyrol, 5 Austria-Hungary, have invented certain new and useful Improvements in Permanent Ways, of which the following is a specification.

In the endeavor to provide a permanent way which is really equal to modern requirements attempts have been made, first, to strengthen the rails; secondly, to improve the joints of the latter, and, finally, to produce a better ballast. My invention is the result of further pursuit in this direction with a view 15 to increasing the carrying power of the rails and to enabling the ballast to more perfectly fulfil the duties of the special supporting and fastening means usually employed for the rails.

20 For the purpose in view, sleepers being dispensed with, I partly replace the ordinary gravel ballast by beaten or stamped cement ballast, (if desired, provided with iron strengthening members,) which more or less, directly 25 or indirectly, surrounds the rails, whereby special supporting and fastening members, of whatever description, are rendered unnecessary, the ballast, with the rails embedded in it, constituting an extremely-durable girder. 30 The advantages of my system of thus embedding the rails in ballast consist in the simplification of the structure as a whole, the absence of sleepers and fastening devices, increased resistance of the permanent way to 35 vertical and lateral forces exerted by rapidly-traveling loads, independently of the rail-section and atmospheric influences. Thus safe running is promoted, and at the same time the costs of maintenance reduced.

40 My invention is illustrated by the accompanying drawings, in which—

Figure 1 is a cross-section of a permanent way suitable for light traffic. Fig. 2 is a cross-section of a level crossing constructed according to this invention. Fig. 3 is a cross-section of a permanent way adapted for heavier traffic.

Fig. 4 is a cross-section of a permanent way more especially adapted for use when my invention is to be applied to existing railways. Fig. 5 is a longitudinal section through Fig. 4. 50 Fig. 6 is a plan of Fig. 5. Fig. 7 is a detail view to be hereinafter referred to.

In the permanent way shown in Fig. 1, and more particularly adapted for light traffic, the rails 1 are embedded in stamped concrete 2 in 55 such manner that only the tread and the inner side of the head of the rails are left exposed. The stamped concrete forms a part of the ordinary gravel ballast 3, which lies in the normal manner on the ordinary earthwork 4. 60 The concrete may take the form of a continuous uninterrupted course or of short blocks or lengths. The first method most perfectly realizes the advantages above stated, since the rails and ballast are then united to form a continuous concrete iron girder. 65

Fig. 2 illustrates a suitable method of constructing level crossings or tramway-lines according to my invention. As in Fig. 1, only the tread and the inside surface of the heads 70 of the rails remain exposed. The central channel for draining the track is omitted and two small grooves 5 are provided in the concrete for the flange of the wheel.

The above-described permanent way, however, while presenting the advantages already referred to, requires supplementing if it is intended to withstand the wear and tear of express traffic. For this purpose, so far as the forces acting in vertical direction require it, 75 the lower portion of the concrete is strengthened by any desirable number of iron rods 6, bars, wires, or the like stamped into the concrete and running parallel to and preferably directly below the rails, as shown in Fig. 3. 80 Forces acting in lateral direction are met by iron transverse strengthening members 7, which may advantageously have hooked ends, trending upward and then downward. Other strengthening members may be arranged 85 crossing—i. e., obliquely to—the said members 6 and 7, and thus uniting the properties 90

of both to some extent. To construct a permanent way of this description, however, is not well practicable on existing railways on which there is heavy service, in view of the time required for the concrete to thoroughly harden.

Figs. 4 to 6 illustrate the system adopted by me for providing a stamped concrete permanent way in such cases—that is, on existing railways, where continued motion of the rails on the one hand and the slow hardening of the concrete on the other hand have both to be taken into account. In such cases the sleepers should not be at once dispensed with, but must be spaced out as far as possible. The concrete has then to be laid in the spaces between the sleepers in such manner that the rails and concrete do not contact with each other, as Fig. 4 shows. Channels 8 are thus formed, the walls of which may approach each other toward the top, Fig. 4, or toward the bottom, Fig. 7, or may run vertically upward, and in these channels the rails can move freely under the passing load. After the concrete has perfectly hardened these channels 8 are filled up with any suitable rapidly-hardening and preferably elastic mass—*e. g.*, some kind of asphalt preparation, whereby the rails receive a certain firm packing—rails, concrete, and moving body being thus saved wear and tear. The sleepers can now be removed and the gaps thus left filled up in the manner already described with stamped concrete, whereby a continuous concrete ballast is formed. Finally the channels of this subsequently-laid concrete are filled up also, so that the rails are firmly and elastically connected throughout their entire length.

The form of channel illustrated in the detail view Fig. 7 facilitates removal of the filling mass in the case of repairs or relaying of rails.

It may be added that the last-mentioned method of forming the permanent way can un-

der certain conditions also be advantageously employed in constructing new railways.

What I claim is—

1. A permanent way comprising stamped concrete, rails lying in the concrete, and strengthening members embedded in the concrete and extending parallel with, and beneath the level of the rails, substantially as described.

2. A permanent way comprising stamped concrete, rails lying in the concrete, and strengthening members embedded in the concrete and extending parallel with, and under the rails, substantially as described.

3. A permanent way comprising stamped concrete, rails lying in the concrete, and strengthening members embedded in the concrete below the level of the rails and extending transversely thereof, substantially as described.

4. A permanent way comprising stamped concrete, rails lying in the concrete, and strengthening members embedded in the concrete and each extending transversely of the rails and under both of them, substantially as described.

5. A permanent way comprising stamped concrete, rails lying in the concrete, and strengthening members embedded in the concrete below the level of the rails, some of said members extending parallel with the rails and the others transversely thereof, substantially as described.

6. A permanent way, comprising stamped concrete lying upon a suitable bed and provided with channels, and rails lying in said channels and held therein by a quickly-hardening filling mass, substantially as described.

In testimony that I claim the foregoing I have hereunto set my hand this 24th day of March, 1903.

RAFAEL V. MEINONG.
